UNITED STATES PATENT OFFICE.

EUGÈNE MOREAU, OF SAN FRANCISCO, CALIFORNIA, ASSIGNOR TO THEO. DORE W. STERLING, OF NEW YORK, N. Y.

HAND ROCK-DRILL.

SPECIFICATION forming part of Letters Patent No. 268,427, dated December 5, 1882.

Application filed March 14, 1882. (No model.)

To all whom it may concern:

Be it known that I, EUGÈNE MOREAU, of the city of San Francisco, in the State of California, have invented a certain new and useful Improvement in Hand Rock-Drills, of which the following is a full, clear, and exact description.

This invention more particularly relates to hand rock-drills in which are combined a series of hammers arranged to revolve in concert about a common center, and each of which is successively brought in line with the drill or the drill-holding spindle by the mechanism which revolves the series of hammers, and which, acting in concert with other devices, causes each hammer to deliver its blow upon the drill or drill-holding spindle that is made to continuously revolve, substantially as described in an application for patent made by me and filed 20 in the United States Patent Office on the 28th day of January, 1882.

The invention consists in a novel method of automatically feeding the drill, and means therefor, whereby the drill is made to advance 25 toward the rock as fast as required by the progress of the boring.

It also consists in a certain combination of swivels and slides with the stand which carries the machine, whereby the machine may 30 be easily and quickly placed in any desired position; also embraces other details of construction, whereby increased facility is afforded for operating the drill, substantially as hereinafter described.

Reference is to be had to the accompanying drawings, forming part of this specification, in which similar letters of reference indicate corresponding parts in all the figures.

Figure 1 is a longitudinal vertical section of a hand rock-drill having my invention applied. Fig. 2 is a partially-sectional longitudinal elevation of the front part of said machine, showing the hammers and a stationary cam used in their operation. Fig. 3 is a longitudinal vertical section of the front part of the machine, in illustration of the action of the automatic feeding mechanism. Fig. 4 is a top view of the machine, with the cover removed, for the purpose showing the gears, hammers, and other parts 50 inclosed by the tubular frame of the machine.

Fig. 5 is a rear elevation of the machine. Fig. 6 is a vertical cross-section of the same on the line *xx* in Fig. 4, looking from the rear of the machine; and Fig. 7 a vertical cross-section on the line *yy* in Fig. 4, looking from the front 55 of the machine.

A in the drawings indicates a tubular box made to open on its top side nearly throughout its length, as shown in Figs. 4 and 6, and closed by a cover, *B*, hinged on its one side, 60 as at *b*, and engaging with a latch, *c*, on its opposite side. This cover protects the internal part of the machine from dust and flying fragments of rocks or injury from other causes.

At the front end of the machine is secured, 65 by means of bolts, a flange, on which is cast the cam *C* that lifts the hammers and that has a central hub, *d*, bored to receive the journal of the central shaft, *D*. The rear end of this shaft *D* rests in a step-bearing, *e*, cast with the 70 box *A*, and near said bearing is a bevel-wheel, *E*, fast on the shaft *D*.

G indicate the hammers, arranged at equal distances from each other around and parallel with the shaft *D*, and at uniform distances 75 from the axis of said shaft. These hammers are carried by and free to slide within or through disks or flanges *H* *I*, fast on the shaft *D*, whereby on the rotation of the shaft *D* the series of hammers rotate with it about a common center and are guided in their longitudinal movements. Springs *J* serve to press the hammers forward. Each hammer is restrained from rotating about its own axis by means of a roller, *f*, on it arranged to travel within a slot 80 in the flange *H*, and each hammer *G* has another roller, *g*, on it, which bears, by the pressure of the spring *J*, against the stationary cam *C*, which is of suitable construction on its face to cause each hammer in succession, as the series 85 of hammers are revolved in concert with the shaft *D*, to be suddenly and forcibly thrown forward by its spring *J*, and deliver its blow on the rear end of the drill-spindle *K*, which carries on its forward end, by means of a connecting-clamp, the drill *h*, and which has a leather or other soft or elastic washer, *i*, interposed between a flange, *k*, on said spindle and the forward end of the main frame or box secured 90 thereto. The drill is rotated while the blow is 95 100

being imparted to it, and is kept constantly rotating by means of a pinion, l , on the central rotating shaft, D , arranged to gear with a wheel, m , on the drill-spindle.

5 Near the rear end of the box A , and cast at right angles with it, is a sleeve, L , that receives within it a shaft, M , to which is secured a bevel-wheel, F , that gears with the bevel-wheel E on the shaft D . The inner end of the 10 shaft M rests in a step-bearing, n , cast with the box A . A fly-wheel, N , having a crank-handle, o , is keyed on the outer end of the shaft M .

On what may be termed the "under" part 15 of the box A , extending throughout its length, is cast a V-shaped slide, P , which is planed to fit correspondingly-shaped grooves or recesses in a right-angularly shaped support, Q , to provide for the passage of the slide P through 20 said support.

Under or along one side of the box A , and parallel with the shaft D , is a screw, R , arranged to rotate in bearings provided for it in the ends of said box, but restrained by suitable collars on it from longitudinal movement. 25 This screw R works through a nut, r , on the supports Q .

On the outer end of the screw R is keyed a handle or hand-wheel, S , for operating it, and 30 on the opposite or inner end of said screw is fitted a loose pinion, t , and a sliding clutch or sleeve, u , which is constructed to engage with and disengage from said pinion according to the direction in which the sleeve is slid upon 35 the smooth inner end portion of the screw R . The sleeve u is fitted to turn with the screw R , as well as to slide independently along it, by means of an internally-projecting pin on the sleeve, arranged to pass through a longitudinal 40 slot in the screw, as shown in Figs. 1 and 3, or said sleeve may be otherwise equivalently fitted. When the sleeve u is pushed against the pinion t said pinion cannot turn without imparting the same motion to the sleeve; but 45 when said sleeve is drawn away from said pinion the motion of both are independent. The sleeve u has a circular groove in or around it for the purpose of receiving the end of a lever, v , pivoted intermediately of its length at w .

50 Secured on the drill-spindle end of the box A or flange thereon is a casting or box, S , bored to receive the drill-spindle K , which has a groove cut around an enlarged portion of it to receive within it the opposite end of the lever v to that which engages with the sleeve u .

Fastened to the box S is a spring, a' , which bears against the lever v , to push the spindle K forward, and at the same time to press the sleeve u against and into clutch-connection 60 with the pinion t .

The wheel m on the head of the drill-spindle is fitted thereto by a spline or feather, so that said spindle can be made to move back and forth independently of the wheel m , but is necessitated to rotate with it.

65 An intermediate gear-wheel, b' , connects the

pinion l on the shaft D with the pinion t on the screw R .

The box S is constructed to cover all the front gearing, thus protecting it from injury.

The slide seat or support Q is secured by a swivel-bolt, d' , to a split sleeve, A' , which is fitted to slide up and down or along a column, B' , and is made capable of turning thereon to adapt the drill to different positions of working, and when the machine has been thus adjusted, as required, it is held in position by a screw-bolt, c' , applied to the split portion of the sleeve.

In operating the drill, rotary motion is imparted to the fly-wheel N , and is transmitted through the bevel-gears E F to the shaft D , whereby, and through the agency of the flanges H I , springs J , and stationary-cam C , the hammers, rotating in common with the shaft D , but 85 not on their own axes, are made to successively deliver their blows on the head of the revolving drill-spindle K . Each blow is immediately transmitted to the drill-point or drill proper, h .

To prevent the friction which would be caused 90 by contact of each hammer with the head of the spindle, after the delivery of the blow and before the hammer is pushed back again by its travel over the face of the stationary cam C , the spring J of each hammer is made of such 95 length as that it is fully expanded before the contact of the hammer with the spindle takes place. At the moment of contact the hammer rebounds, as the spring is too short to press it against the spindle, and thus the friction referred to is avoided.

The machine can be made to go forward or backward on its support by suitably turning the hand-wheel S , and with it the screw R , working through the nut r on the support Q , 105 which has a fixed relation. If, however, the operator is so engaged by working at the crank O of the fly-wheel N as to be unable to use the hand-wheel S , it is then desirable to so connect the feed-screw R with other parts as to cause 110 the machine to move forward automatically. To accomplish this the clutch or sleeve u on the end of the screw R is connected by the lever v with the grooved head of the spindle K , which has a longitudinal movement in its 115 bearing of about three-eighths of an inch, more or less, Fig. 1 showing it in its extreme forward position, and Fig. 3 exhibiting it in its extreme backward position.

Supposing the parts to be placed as indicated in Fig. 1, and that the point of the drill does not bear against the rock, the blows of the hammers on the drill-spindle will be received by the leather-washer i , and in this position of the spindle the sleeve u is pushed into 125 clutch-connection with the pinion t . Now, as the pinion t is driven by the wheel b' , which derives its motion from the pinion l on the shaft D , the rotary motion communicated to said pinion t is transmitted through the sleeve 130 u to the screw R , thus drawing the machine forward. This forward movement of the ma-

chine will continue until the drill-point comes in contact with the rock, and, upon the machine being fed forward faster than the boring is accomplished, the drill-spindle K will assume the position shown in Fig. 3. In that position of said spindle the sleeve u has been drawn away from the pinion t, and said pinion continues to revolve without affecting the sleeve and screw R. Consequently the machine remains stationary until the progress of the boring has again allowed the spindle K to move forward, and has again caused the sleeve u to connect with the pinion t for the purpose of automatically feeding the machine forward, as before.

By means of the hereinbefore-described connection of the support Q with the split sleeve A', made adjustable both along and around the column B', the machine can be set and held in place vertically, horizontally, or at any desired angle and in any direction from the axial line of the column as a center.

It will also be noted that with the addition of the two bevel-wheels E F and shaft M, arranged in a line which is parallel with the swivel-bolt d', the fly or operating wheel remains always in a vertical and convenient position for working in the various changed positions of the machine.

It will also be noticed that by means of the step-bearings e and n for the shafts D and M, friction is reduced by causing said bearings to receive the thrust of said shafts.

Having thus fully described my invention, I

claim as new and desire to secure by Letters Patent—

1. In a rock-drill, the combination, with a slotted sliding sleeve, u, and slotted spindle K, connected by a middle-pivoted lever, v, of a spring, a', arranged to act upon one arm of the lever and simultaneously force the spindle down and the sleeve up, as and for the purpose specified.

2. The combination of the rotating and sliding drill-spindle K, the longitudinally-sliding hammers G and their springs J, the rotating shaft D, by which the longitudinally-sliding hammers are made to rotate around the axis of said shaft, the gears l m b', and loose pinion t, the screw R, by which the sliding box or frame portion A of the machine is fed forward, and on which the loose pinion t is arranged, the longitudinally-sliding sleeve or clutch u, fitted to rotate in common with said screw and engaging with the pinion t, the lever v, and the spring a', essentially as and for the purposes described.

3. The screw R, having end sleeve, u, the lever v, and the spindle K, having a slight longitudinal play in its bearing, in combination with a pinion, t, wheel b', and pinion l on shaft D, whereby the machine will be moved forward until the drill comes in contact with the rock, as described.
